PARACHUTE DART

Paul R. Swearingen, Kensington, Ohio

Application August 5, 1957, Serial No. 47,224

Term of patent 14 years

(Cl. D34—15)

Fig. 1 is a perspective view of a parachute dart, showing my new design in ascending position; and

Fig. 2 is a perspective view thereof in descending position.

The broken line showing of a projector in Fig. 1 is for illustrative purpose only.

I claim:

The ornamental design for a parachute dart, substantially as shown and described.
